Primary Examiner — Wan Laymon(74) *Attorney, Agent, or Firm* — Warner Norcross and Judd LLP(57) **CLAIM**

The ornamental design for an ultrasound device, as shown and described.

DESCRIPTION

FIG. 1 is a perspective view of the ultrasound device embodying the new design;

FIG. 2 is a right side view of the design, the left side view being a mirror image thereof;

FIG. 3 is a front view thereof;

FIG. 4 is a rear view thereof;

FIG. 5 is a top view thereof; and,

FIG. 6 is a bottom view thereof.

The portions shown in broken lines in FIGS. 1-6 are shown for environmental purposes and form no part of the claimed design. The broken lines immediately adjacent to solid lines form the boundary of the claimed design.
